CALIFORNIA.

BOAT-DAVIT.

1,303,750.

Specification of Letters Patent. Patented May 13, 1919.

Application filed May 8, 1918. Serial No. 237,152.

To all whom it may concern:

Be it known that we, WILLIAM J. WILKINSON and BERNARD HEDSTROM, citizens of the United States, residing at Oakland, Alameda Co., and San Francisco, San Francisco Co., respectively, and State of California, have invented certain new and useful Improvements in Boat-Davits, of which the following is a specification.

10 This invention relates to improvements in devices for hoisting and lowering boats over a ship's side and more particularly to a davit of the quadrant type.

The principal object of our invention is 15 to provide a davit having a power controlled boom which is adapted to swing the boat a considerable distance from the side of the vessel. A further object of the invention is to so arrange the controlling mechanism for 20 these booms that when the free ends of the latter are in their outermost position the greatest amount of power is exerted by the operating mechanism to control the movement thereof and as the boom assumes an 25 upright position the amount of power necessary to cause the same movement is considerably less. Thus, at the point where the greatest weight and consequently the greatest strain is imposed on the boom and 30 associated parts, the power applied thereto is in direct proportion.

A further object of the invention is to 35 provide a device of this character which is readily operated by a minimum number of persons and in which the weight of the boat will not in itself operate the lowering mechanism, thus preventing one boom from being suddenly lowered with the attendant danger of spilling out the occupants of the boat.

40 With these and other objects in view, the invention consists of certain novel features of construction, combinations and arrangements of parts hereinafter described and more specifically pointed out in the appended claims; it being understood that changes 45 in form, proportion, size and minor details of construction within the scope of the claims may be resorted to without departing

from the spirit of the invention or sacrificing any of the advantages thereof. 50

Referring to the drawing forming a part of this specification,

Figure 1, is a view in end elevation showing the improved davit mounted on the deck of a vessel. 55

Fig. 2, is a view in front elevation, the mechanism at one end being in section.

Fig. 3, is a view in section on the line 3—3, Fig. 2.

Fig. 4, is a view in side elevation showing 60 a modified form of gear for operating the boom.

Referring to corresponding parts of the several views by the same numerals of reference, 1 denotes the boat deck to which are 65 attached, in any suitable manner, the right and left hand stands 2 and 3. These stands are similar in construction and the description hereinafter will apply for both.

Each stand consists of a base plate 4 from 70 which rise the sides 5 and 6 that in turn are connected by cross plates 30. These stands may be constructed of suitable structural shapes riveted or bolted together or they may be made of cast material. Near the top 75 of the frame is a shaft or pin 7 extending through from one side to the other, on which is pivotally mounted the boom 8. This boom is of sufficient length to extend outwardly over the edge of the boat deck and lower a 80 boat to the water line even when the ship is listing to a considerable extent. As here shown it consists of two channels placed back to back and riveted together, and to the joined webs we attach the flanged sleeve 34 85 to secure a large bearing on the pin 7. On the upper end of the boom is attached a curved head 9, the outer end of which is provided with a lug 10. Pivotally attached to this lug is link member 11 and to the opposite end of the latter is pivotally attached a tackle block 12.

The boat is denoted by 13 and on each end is provided with suitable means for engagement with the hooks 14 which are attached 95 to the lower tackle block 16. These blocks

may have any required number of pulleys over which passes a rope or cable 17, the free end of which is fastened around a cleat (not shown) when the boat is positioned on a 5 deck.

- Secured to the inner end of the boom, as by riveting between the channels of which the boom is formed, is a plate 19, the outer edge of which is eccentric with the shaft 10 7. A segmental internal toothed gear 20 is provided having the same form as the edge of plate 19, and to which it is attached by bolts 32 extending through the plate and lugs 31 formed on the segment.
- Secured to the side 6 is a stud bolt 22 on which is revolvably mounted the worm wheel 23 and the eccentric toothed gear 21. This worm and gear are in turn secured to each other and the eccentricity of the gear is 15 such that it properly coacts with the segment 20. It will be understood that by eccentric we do not mean merely a circle which is off center from a given point, but include other curves which deviate from a 20 circle and which may or may not have their centers in the axis of rotation.

Meshing with the wheel 23 is a helical worm 24 which is attached to a shaft 25 that has attached on its opposite end one side of 30 the universal joint 33. Shaft 25 is revolvably mounted in bearings 26 which in turn are attached to the side 6. A short shaft 35 is revolvably mounted in a bearing 27 and in the plate 30 and on the inner end is attached 35 to the other side of the universal joint and on the outer end has attached thereto the crank handle 28.

In the modified form shown in Fig. 4, the toothed gear 40 which co-operates with the 40 segment 41 is made in the form of a spiral, the center of which is the axis of shaft 22. By this arrangement the effect which we desire to obtain can be accentuated.

Assuming a boat to be positioned as 45 shown, the operation is as follows:—By turning the crank handle 28, the shafts 27 and 25 are rotated causing the worm 24 to turn the wheel 23 and hence the toothed gear 21. The latter in turn moves the segment 20 and so swings the boom 8 outwardly.

Now, each successive position of the arm, as the latter moves outwardly until it reaches a horizontal position, increases the 55 force which the weight of the boat and its occupants exert on the inner end of the arm, and consequently through the toothed gears against the efforts of the person who is operating the crank handle. As we construct the segment 20 eccentric with the pivotal point 7, the eccentricity being such that 60 when the arm is substantially horizontal,

the ratio between gears 21 and 20 is the least, it will require substantially the same effort to be exerted on the crank handle to move 65 a given weight when the boom is horizontal as when it is in an approximate vertical position.

It will also be apparent that by selecting the proper pitch for the threads of worm 24, 70 the mechanism will be irreversible, that is, the weight on the outer ends of the davits can never cause rotation of the worm and shaft in case the handle 28 is free.

We claim as new and wish to cover by 75 Letters Patent:—

1. A davit comprising a stand, a boom pivotally mounted in said stand intermediate its ends, an eccentric toothed segmental gear carried by the inner end of said boom, 80 a pivotally mounted eccentric toothed gear adapted to coöperate with the aforesaid gear, and means for rotating said last mentioned gear.

2. A davit comprising a stand, a boom pivotally mounted in said stand intermediate its ends, a curved head on the outer end of said boom adapted to suspend a boat, a toothed segmental gear attached to the inner end of said boom, said gear being eccentric 90 with the axis of said boom, a revolvably mounted toothed eccentric gear adapted to coöperate with said segmental gear, and means for rotating said last mentioned gear.

3. A davit comprising a stand, a boom pivotally mounted therein, and toothed gear means for moving said boom through varying angular distances for a given movement of the driving mechanism. 95

4. A davit comprising a pivotally mounted boom, a segmental toothed gear attached to said boom, an operating gear coöoperating with said segmental gear, said gears having a pitch line eccentric to the axis of said boom, and means for rotating said operating gear. 100

5. A davit comprising a pivotally mounted boom, a toothed gear having a pitch line eccentric to the axis of said boom attached to said boom, a toothed gear adapted to 110 drive the aforesaid gear, and means for driving said last mentioned gear.

6. A davit comprising a pivotally mounted boom, a toothed gear carried thereby, a coöoperating toothed gear for driving the aforesaid gear, said gears having a pitch line eccentric to the axis of said boom, and means for driving said last mentioned gear. 115

7. A davit comprising a pivotally mounted vertically movable boom, an internally toothed segmental gear carried by said boom, an eccentrically mounted gear adapted to mesh with said segmental gear, a worm wheel movable with said last mentioned 120 gear.

gear, a driving worm, and means for rotating said worm.

8. A davit comprising a pivotally mounted boom, a segmental toothed gear attached to said boom, an operating gear coöperating with said segmental gear, said gears having a varying pitch line so that said boom moves through different angular distances for a given angular movement of the operating gear, and means for rotating said operating gear.

9. A davit comprising a pivotally mounted boom, a toothed gear having a pitch line non-concentric with the axis thereof attached to said boom, an operating gear having teeth adapted to coöperate with said first mentioned gear, and driving means for said operating gear.

10. A davit comprising a pivotally mounted boom adapted to swing from a substantially vertical position to a substantially horizontal position, a toothed gear carried by said boom, a driving gear coöperating therewith, said gears having a variable pitch

ratio which decreases as the boom moves 25 from vertical to horizontal, and means for rotating said driving gear.

11. A davit comprising a pivotally mounted, vertically movable boom, an internally toothed segmental gear carried by said 30 boom, and having a pitch line non-concentric with the pivotal axis of said boom, an operating gear for driving said segmental gear, and an irreversible driving means for said operating gear.

12. A davit comprising a pivotally mounted boom, a segmental toothed gear attached to said boom, an operating gear coöperating with said segmental gear, said gears having a pitch line non-concentric to the axis of 40 said boom, a worm wheel movable with said operating gear, a driving worm, and means for rotating said worm.

In testimony whereof we affix our signatures.

WILLIAM J. WILKINSON.
BERNARD HEDSTROM.
